UNITED STATES PATENT OFFICE.

AUGUSTUS D. KLABER, OF LONDON, ENGLAND.

COPYING-MACHINE.

No. 843,556.

Specification of Letters Patent.

Patented March 26, 1907.

Application filed November 22, 1906. Serial No. 344,576.

To all whom it may concern:

Be it known that I, AUGUSTUS D. KLABER, a subject of the King of Great Britain, residing at London, England, have invented a certain new and useful Improvement in Copying-Machines, of which the following is a specification.

This invention concerns copying-machines of the type commonly used in offices for obtaining impressions of letters and other matter written either by hand or on the typewriter.

The object of the invention is to effect certain improvements in the construction and arrangement of the parts of machines of this character, and particularly of machines of the type disclosed in an application filed by me October 28, 1905, and serially numbered 284,920.

The novel features of my invention are illustrated in the accompanying drawings, which show the preferred embodiment thereof, and in which—

Figure 1 is a central section of the machine. Fig. 2 is a detail view showing the construction of the supply-roller. Fig. 3 is a plan view of the receiving-roller and cutting device, and Fig. 4 is a horizontal section on line 4-4 of Fig. 1.

Referring to the drawings, the machine consists generally of a frame having mounted thereon a supply-roller 1, on which a continuous web of copying-paper is wound, two copying-rollers 2 and 3, between which the web and the impression-sheets pass, a receiving-roller 4, on which the web is wound after passing between the copying-rollers, and a cutting device for cutting the web upon the receiving-roller. The frame has side members 5, on the upper edges of which are mounted the upright end members 7 of the casing for the supply-roller 1. Secured to these end members is a semicircular sheet-metal piece 8, having pivoted thereto at one of its edges a similar sheet-metal piece 9. The edge of the piece 8 opposite that to which the piece 9 is pivoted is curled, as indicated at 10, to form a rounded surface, over which the web of copying-paper 11 is drawn, and the adjacent edge of the piece 9 extends in close proximity to the curled portion 10, so that when the casing is closed this edge extends close to or touches the web 11. The pieces 8 and 9 are so constructed that when the latter is in the closed position the edges

adjacent to the pivot are in engagement. In this way the casing for the supply-roller 1 is practically air-tight, and little drying of the web of copying-paper takes place.

In Fig. 2 is shown the construction of the supply-roller 1. This consists of a metallic tube 12, having a slot cut therein and a strip 13 secured within the tube and having a part extending through the slot beyond the periphery of the tube. This strip is of thin metal, so as to yield somewhat, but exerts an outward pressure whenever depressed. In this way a roll of the copying-paper is held firmly upon the supply-roller even though it or the tube on which it is wound does not fit tightly upon the roller. In the ends of the tube 12 are secured end members 14, having integral pintles projecting therefrom and forming pivots for supporting the roller in bearings in the end members 7 of the casing.

Pivotedly mounted on the members 5 of the frame are two bell-crank levers 15, the outer ends of which are connected by a rod 16, having a handle 17 thereon. In the opposite ends of these levers is pivotally mounted the copying-roller 2, which is preferably of rubber. The other copying-roller 3 is mounted for rotation in bearings in the frame members 5 directly below the roller 2 and in the position shown in Fig. 1. This roller preferably has a hard surface. When the roller 2 is in the position illustrated in Fig. 1, it and the roller 3 are pressed into hard engagement; but by raising the handle 17 roller 2 is carried away from roller 3 to avoid injury to the surface of roller 2 when the machine is not in use.

Extending across between the side frames 5, adjacent and parallel to the copying-roller 2, is a rod 18, and loosely mounted on this rod are a plurality of strippers 19. The rod 18, carrying these strippers, is so positioned that the strippers swing by gravity to a position in which they bear against the surface of the roller 2. On the shaft of the roller 3, beyond the frame member 5, is a gear 20, meshing with a pinion 21, mounted on a stud-shaft 22, which has secured thereto an operating-handle 23. Mounted upon the side frames 5 is a feed-board 24, so located with reference to the copying-rollers that the impression-sheets are fed therefrom onto the upper surface of the roller 2 and between that roller and the web of copying-paper. The sheets pass around substantially half the circum-

ference of the roller 2 in contact with the web, which presses lightly thereon and smooths the sheet out, and then between the copying-rollers 2 and 3, which produce the impression upon the web. They then fall into a suitable receiving-tray, while the web is carried down to and wound upon the receiving-roller 4. If the impression-sheet tends to adhere to the copying-roller 2, it is stripped therefrom by the strippers 9, which bear at all times against the periphery of the roller 2.

The receiving-roller 4 consists of a shaft having end members 25 mounted thereon and a plurality of bars 26 extending between these end members with their ends entering openings therein. As each impression on the web, together with the margins allowed therefor, must form one convolution upon the receiving-roller, it is highly desirable that the circumference of this roller be adjustable to adapt the machine for use with sheets of varying dimensions. I therefore provide in each of the end members 25 a number of openings 27 greater than the number of bars 26 and spaced at unequal distances from the center of the roller, as shown in Fig. 1. With this construction when the circumference of the receiving-roller desired is obtained, the bars 26 may be positioned in such of the openings 27 as will give this circumference. The receiving-roller is driven by a belt 28, running on pulleys mounted one on the shaft of the roller 3 and the other on the shaft of the receiving-roller 4. In order to cut the web of copying-paper upon the receiving-roller when a number of impressions have been taken, I provide a knife-blade mounted upon the frame of the machine and actuating devices for moving this blade toward and away from the receiving-roller. This blade is shown at 29 and is secured on a bar 30, having inclined slots cut therein, such that when the bar is moved lengthwise by the handle 31 it is caused to move toward the receiving-roller, as described in my pending application above mentioned. In order to effect a clean cut, a rod 32 is mounted upon the receiving-roller and has a slot cut therein into which the knife-blade enters, the walls adjacent to the slot holding the paper against being pressed inwardly by the blade. Immediately in rear of this rod, around the receiving-roller, is a thin sheet-metal strip 33, pivoted upon the end members of the receiving-roller at 34. A spring 35 is secured at one end to this strip and at the other to the end member of the receiving-roller and operates to hold the pivoted strip 33 either in the position in which it is shown in Fig. 1, with its edge entering a groove in a rod 36, extending between the end members of the receiving-roller, or in a position in which it bears against the rod 32. One of the pivots of this strip extends through

the end member of the roller and has an operating-handle 37 secured thereon. This spring-actuated strip is used for gripping the end of the web of copying-paper to the receiving-roller, and it will be seen that the strip is positioned directly in rear of the point on the receiving-roller where the web is severed, so that when the web is cut its end can readily be placed against the rod 36, while the strip 33 is held in the open position by spring 35 and the strip then turned by handle 37 to grip the web between it and the rod 36. The strip 33 may, if desired, be thrown automatically to this gripping position. When the strip is moved to the open position after making a cut, a shield 38, overlying the knife-blade 29, lies directly below it, and therefore the initial movement of the receiving-roller when rotation thereof is commenced causes the strip to engage the shield 38 and be turned thereby to the closed position, in which it grips the end of the web. When the knife-blade has been operated, the severed portion of the web may not fall away from the receiving-roller immediately. If not, the operator may rest one finger on shield 38 and turn handle 37 with his thumb, thus turning strip 33 on its pivot and throwing the end of the severed portion of the web down upon his finger, when he can readily grasp it.

In order that the web wound on the receiving-roller may always be cut at the proper point, I provide means for indicating when the slot in the rod 32 is directly opposite the knife-blade 29. Secured on one of the side frames 5 of the machine is a bracket 39, having an inwardly-turned finger 40 at its end which closely overlies one of the end members 25 of the receiving-roller. On this end member is a mark 41, so positioned that when it is directly under the finger 40 the slot in rod 32 is directly opposite the knife-blade 29, and the operator can by glancing at this indicator tell when he may operate the cutting device.

In a machine of this type in which the web is wound on a receiving-roller and cut while wound thereon it is of great importance that the impression-sheets be introduced into the machine when the receiving-roller is in a definite position, so that the impression made therefrom will be so disposed upon the receiving-roller that the cut through the web will leave just the proper amount of margin on either side of the impression. I therefore provide an automatically-operated feeding device for the impression-sheets controlled by the receiving-roller. Mounted in bearings in the side frames 5 is a rock-shaft 42, on which is secured an arm 43, having a stud 44 at its end. This stud engages the periphery of a cam 45, keyed upon the shaft of the receiving-roller 4. Secured on rock-shaft 42 near its ends

and extending upwardly therefrom are two arms 46, carrying at their free ends a shaft 47, and secured on this shaft are a plurality of arms 48. Adjustably secured to each of these arms is a feeder-arm 49, the end of which extends through a slot in the feed-board 24. The adjustment of the feeder-arms 49 relatively to the arms 48 is secured by means of a set-screw 50, extending through a slot 10 in the arm 48 and into a threaded opening in the feeder-arm 49. By means of this mechanism each revolution of the receiving-roller 4 rocks shaft 42 by means of cam 45 and arm 43, and thus moves the ends of the feeder-arms 49 from a position at the rear end of the slots in the feed-board 24 to the forward end of those slots and then back again, and in this forward movement the feeder-arms carry an impression-sheet which 15 has been laid upon the feed-board to a position in which it is gripped between the copying-roller 2 and the web of copying-paper which is drawn down from the supply-roller 1. Since the length of the arms of the feeding mechanism is adjustable, the machine can readily be adapted for operation with impression-sheets of various sizes.

The pivotally-mounted strippers 19 prevent an impression-sheet from being carried 20 around by the copying-roller 2. In order to prevent a sheet from being carried with the web to the receiving-roller, I provide a stripper-plate 51, extending in close proximity to or actually touching the web of copying-paper passing from roller 3 to the receiving-roller 4, so that if an impression-sheet is carried along with the web it will be detached by this stripper-plate. The plate is secured upon the ends of arms 52, whose opposite 25 ends are bifurcate and astraddle the shaft 42. When the stripper-plate is in operative position, as shown in Fig. 1, it is supported by the arms 52 bearing against studs 53 on the side frames. In order to give free 30 access to the parts of the machine—as, for instance, when threading the web of copying-paper through the machine—this stripper-plate is so mounted that it can be moved from its operative position to an inoperative 35 position, as shown in dotted lines in Fig. 1, and in this position the operator can readily pass his hand under the copying-roller 3 in order to grasp the end of the web of copying-paper and carry it over to the receiving- 40 roller.

Having now described my invention, what I claim as new therein, and desire to secure by Letters Patent, is as follows:

1. In a copying-machine, the combination 45 of a supply-roller on which a continuous web is wound, two copying-rollers between which the web and the impression-sheets pass, means for rotating one of said rollers, a receiving-roller on which the web is wound after passing between said rollers, a cutting

device for cutting the web upon the receiving-roller, and a movable part on the receiving-roller rearward of the point thereon where the web is cut adapted to grip the end of the web, substantially as set forth.

2. In a copying-machine, the combination 50 of a supply-roller on which a continuous web is wound, two copying-rollers between which the web and the impression-sheets pass, means for rotating one of said rollers, a receiving-roller on which the web is wound after passing between said rollers, a gripping member pivotally mounted on said receiving-roller, a second gripping member on said roller, and a spring connected to said pivoted member for causing it to grip the web between it and said second gripping member, substantially as set forth.

3. In a copying-machine, the combination 55 of a supply-roller on which a continuous web is wound, two copying-rollers between which the web and the impression-sheets pass, means for rotating one of said rollers, a receiving-roller on which the web is wound after passing between said rollers, a movable part on said receiving-roller for gripping said web and a spring acting thereon to hold it in either the open or closed position, substantially as set forth.

4. In a copying-machine, the combination 60 of a supply-roller on which a continuous web is wound, two copying-rollers between which the web and the impression-sheets pass, means for rotating one of said rollers, a receiving-roller on which the web is wound after passing between said rollers, means for rotating the same, a movable part on said receiving-roller and means actuated by the rotation of said receiving-roller for automatically closing said part to grip said web, substantially as set forth.

5. In a copying-machine, the combination 65 of a supply-roller on which a continuous web is wound, two copying-rollers between which the web and the impression-sheets pass, means for rotating one of said rollers, a receiving-roller on which the web is wound after passing between said rollers, a cutting device for severing the web on the receiving-roller, and a part on said receiving-roller movable to throw the end of said severed portion away from the periphery of said roller, substantially as set forth.

6. In a copying-machine, the combination 70 of a supply-roller on which a continuous web is wound, two copying-rollers between which the web and the impression-sheets pass, means for rotating one of said rollers, a receiving-roller on which the web is wound after passing between said rollers, a movable cutting device for severing the web upon the receiving-roller, a bar on the receiving-roller with which said device coacts and a movable part mounted upon said receiving-roller in rear of said bar, substantially as set forth.

7. In a copying-machine, the combination of a supply-roller on which a continuous web is wound, two copying-rollers between which the web of paper passes, means for rotating one of said rollers, a receiving-roller on which the web is wound after passing between said rollers, an automatically-operated feeding device for feeding impression-sheets between said web and one of said copying-rollers and means for adjusting said device for feeding sheets of varying dimensions, substantially as set forth.

8. In a copying-machine, the combination of a supply-roller on which a continuous web is wound, two copying-rollers between which the web of paper passes, means for rotating one of said rollers, a receiving-roller on which the web is wound, means for operating the same, a feeding device for feeding impression-sheets between said web and one of said copying-rollers, means for operating said device when the receiving-roller is in a definite position, and means for adjusting said device for feeding sheets of varying dimensions, substantially as set forth.

9. In a copying-machine, the combination of a supply-roller on which a continuous web is wound, two copying-rollers, means for pressing said rollers together, means for rotating one of said rollers, a feed-board so located with reference to said copying-rollers that the impression-sheets fed from said board are caused to pass around substantially half the circumference of one of said rollers in contact with said web and then between said rollers, a feed device for the impression-sheets movable relatively to said board and means for adjusting said device for feeding sheets of varying dimensions, substantially as set forth.

10. In a copying-machine, the combination of a supply-roller on which a continuous web is wound, two copying-rollers between which said web passes, means for rotating one of said rollers, a receiving-roller on which the web is wound after passing between said copying-rollers, and means for rotating the same, said receiving-roller having a pair of end members and parts extending between and supported at their ends on said end members and said parts being adapted to be mounted at varying distances from the axis of the roller, substantially as set forth.

11. In a copying-machine, the combination of a supply-roller on which a continuous web is wound, two copying-rollers between which said web passes, means for rotating one of said rollers, and a receiving-roller on which the web is wound after passing between said copying-rollers, said receiving-roller consisting of two end plates and a plurality of bars extending between them with their ends entering openings in said plates, the number of openings in each of said plates

being greater than the number of said bars, substantially as set forth.

12. In a copying-machine, the combination of a supply-roller on which a continuous web is wound, two copying-rollers between which the web of paper passes, means for rotating one of said rollers, a receiving-roller on which the web is wound after passing between said copying-rollers, means for rotating the same, a cutting device mounted adjacent to said receiving-roller and movable toward and away from the same for cutting the web wound thereon, and means for indicating the proper position of the receiving-roller for operating said cutting device, substantially as set forth.

13. In a copying-machine, the combination of a supply-roller on which a continuous web is wound, two copying-rollers between which said web passes, a receiving-roller on which the web is wound after passing between said copying-rollers, means for rotating said receiving-roller and one of said copying-rollers, a cutting device mounted opposite said receiving-roller, means for actuating the same to cut the web upon the receiving-roller, and a stationarily-mounted indicator coacting with a mark on the receiving-roller to indicate the proper position of said roller for operating said cutting device, substantially as set forth.

14. In a copying-machine, the combination of a supply-roller on which a continuous web is wound, two copying-rollers between which said web passes, a receiving-roller on which the web is wound after passing between said copying-rollers, means for rotating said receiving-roller and one of said copying-rollers, a rod mounted parallel and adjacent to said copying-rollers, and a stripper loosely mounted on said rod and bearing by gravity against one of said copying-rollers, substantially as set forth.

15. In a copying-machine, the combination of a supply-roller on which a continuous web is wound, two copying-rollers between which said web passes, means for rotating one of said rollers, a feed-board so located with reference to said copying-rollers that the impression-sheets fed therefrom are caused to pass around substantially half the circumference of one of said rollers in contact with said web and then between said rollers, a rod mounted parallel and adjacent to said copying-rollers, and a stripper for the impression-sheets loosely pivoted on said rod and bearing by gravity against one of said rollers, substantially as set forth.

16. In a copying-machine, the combination of a supply-roller on which a continuous web is wound, two copying-rollers between which the web and impression-sheets pass, a receiving-roller on which the web is wound after passing between said copying-rollers,

and means for cutting the web upon the receiving-roller, said supply-roller having a yielding portion extending beyond the periphery of the roller, substantially as set forth.

17. In a copying-machine, the combination of a supply-roller on which a continuous web is wound, two copying-rollers between which the web and impression-sheets pass, means for rotating one of said rollers, a receiving-roller on which the web is wound after passing between said copying-rollers, means for cutting the web upon the receiving-roller, and a casing for said supply-roller comprising two end members, a sheet-metal member secured thereto, and a second sheet-metal member pivoted to the first and adapted to fit tightly against the same when in the closed position, the free edges of said sheet-metal members extending in close proximity to the web passing from said supply-roller out of the casing and one of said edges being curled, substantially as set forth.

18. In a copying-machine, the combination of a supply-roller having a continuous web wound thereon, a pair of copying-rollers between which the web and impression-sheets pass, a receiving-roller on which the web is wound after passing between said copying-rollers, means for cutting the web upon the receiving-roller, and a stripper-plate mounted for movement from an operative position between said copying and receiving rollers to an inoperative position permitting free access

to the parts of the machine, substantially as set forth.

19. In a copying-machine, the combination of a supply-roller having a continuous web wound thereon, a pair of copying-rollers between which the web and impression-sheets pass, a receiving-roller on which the web is wound after passing between said copying-rollers, means for cutting the web upon the receiving-roller, and a stripper-plate mounted between said copying and receiving rollers, its edge extending in close proximity to said web, substantially as set forth.

20. In a copying-machine, the combination of a supply-roller having a continuous web wound thereon, a pair of copying-rollers between which the web and impression-sheets pass, a receiving-roller on which the web is wound after passing between said copying-rollers, means for cutting the web upon the receiving-roller, and a stripper-plate pivotally mounted and adapted for movement about its pivot from an operative position in which its edge extends in close proximity to said web to an inoperative position permitting free access to the parts of the machine, substantially as set forth.

This specification signed and witnessed this 19th day of November, 1906.
